Attorney's

UNITED STATES PATENT OFFICE.

EDWARD AUSTIN HERR, OF WASHINGTON, DISTRICT OF COLUMBIA.

DESIGN FOR A HOSE-HOOK FOR GARTERS.

No. 38,312.

Specification for Design.

Patented Nov. 18, 1906.

Application filed September 6, 1906. Serial No. 333,578. Term of patent 14 years.

To all whom it may concern:

Be it known that I, EDWARD AUSTIN HERR, a citizen of the United States, residing at Washington, in the District of Columbia, have invented a new, original, and ornamental Design for Hose-Hooks for Garters, of which the following is a specification, reference being had to the accompanying drawing, forming part thereof.

The figure is a plan view of a hose-hook for garters, showing my new design.

I claim—

The ornamental design for a hose-hook for garters, as shown.

EDWARD AUSTIN HERR.
